UNITED STATES PATENT OFFICE.

THEODOR R. WILLWERSCHEID, OF ST. PAUL, MINNESOTA.

LUGGAGE CARRIER.

Application filed November 7, 1921. Serial No. 513,259.

To all whom it may concern:

Be it known that I, THEODOR R. WILLWERSCHEID, a citizen of the United States, residing at St. Paul, in the county of Ramsey and State of Minnesota, have invented 5 certain new and useful Improvements in Luggage Carriers, of which the following is a specification.

This invention relates to luggage carriers, 10 for use in connection with running boards of automobiles, and has for its object to provide a carrier, consisting of a single piece of strap metal, provided with a clamping screw, whereby it may be clamped to 15 the running board, and with means whereby a strap may be attached for holding luggage positioned on the running board.

The principal object of the invention is 20 to provide a device of the class described, of which a plurality may be arbitrarily clamped at various points on the outer edge 25 of the running board, so as to accommodate packages of all shapes and sizes.

Ordinary luggage carriers, as those of the 25 extensible type, simply form a rail along the outer edge of the board, no means being provided, whereby the bundles may be held against bouncing from the running board.

In the present invention any number of 30 devices may be arranged in rows, each device having its own fastening strap, whereby long articles such as tent poles, rolls of canvas and the like, may be firmly strapped to the running board.

For a small single parcel, a single device 35 may be used. A number of the devices may be carried in the tool box of the car, thus eliminating the necessity of carrying an unnecessarily large device like some of those 40 now in use.

A principal object of the invention, however, is to provide a cheap, durable and neatly appearing construction, for attaching 45 the clamping screw to the bent bar.

In the manufacture of articles of this nature, neatness in appearance is of paramount importance, as well as avoiding costly processes in the course of manufacture, such as spot welding, riveting, or machining of parts.

To this end the invention consists in the construction, combination and arrangement of parts hereinafter described and claimed.

The accompanying drawings form part 55 of the specification, in which:

Figure 1, is a perspective view of the invention, shown applied to the running board of an automobile.

Figure 2, is an enlarged side view of my 60 improved luggage carrier.

Figure 3, is a perspective view of the nut retaining member showing it in its folded position.

Figure 4, is a sectional view on line 4—4 65 of Figure 2.

Figure 5 is a plan view of the blank for forming the nut retaining member, and, Fig. 6 is a longitudinal sectional view showing the nut retaining member in assembled 70 relation.

In the drawings, A designates the running board of an automobile, and B my improved luggage carrier. The carrier consists preferably of a bar of channel iron, 75 bent downwardly and inwardly at right angles, thereby forming a cross member 1, a vertical member 2, and an inwardly extending member 3. The channel of the bar is turned inwardly, the outer edge of the legs 80 thereof, resting upon the upper surface of the running board, and the channel in the member 3 opening upward toward the cross member 1. Thus, the bar takes the shape of the letter L, or, a rectangular hook, 85 the hook member 3, having adjacent its outer end an opening 4, which is of a size to loosely receive the thumb or clamping screw 5. Threaded on the thumb screw is the nut 6, which is preferably of the squared 90 variety, and lies in the channel of the member 3, as is best shown in Figure 4 of the drawings.

The thickness of the nut is preferably 95 somewhat less than the depth of the channel, thereby affording a clearance space 7, between the upper face of the nut and the edge of the legs of the channel. The thumb screw 5, is provided with the thumb piece 8, and a bearing plate or swivel washer 9, 100 at its inner end.

The washer is formed with a ball socket

10, adapted to receive the ball 11, at the end of the thumb screw 5, the surrounding wall of the socket being suitably cut away to form notches 12, thereby dividing it circumferentially into a plurality of thin lugs 5 adapted to be bent inwardly over the ball 11 of the bolt. Thus, in assembling the device, the thumb screw 5 is inserted through the opening and the bearing washer 9 then 10 secured to the ball 11 of the screw.

For the purpose of confining the nut 6 in the channel of the member 3, I provide a casing, or, what may be termed, a nut retaining member 13, which will be so formed, 15 that it may be telescoped over the end of the channel and frictionally slid lengthwise of the channel. This casing is formed of a strap of metal, the blank of which is shown in Figure 5, said blank consisting of 20 a long rectangular band 14, having transverse parallel bending lines 15, 16, 17 and 18, these bending lines being disposed in the manner, to form three square areas or sections, namely a center section *a*, and end 25 sections *b*—*b*.

When the blank is bent at right angles, on these bending lines, the square plate sections will take the positions shown in Figure 3, the plate members *b*—*b* overlapping each 30 other, so as to contact flatly, while the member *a* forms a top wall parallel with the sections *b*—*b*, thus forming a rectangular collar which is constructed so as to be frictionally slid over the channel bar. The band may 35 be said to be wrapped around the channel.

Each of the square sections, as *a* and *b*—*b*, have centrally, a bolt hole 19, said holes being arranged to cause them to register when the device is in its folded position.

40 In assembling the parts, the casing is first slid into position to bring its holes 19 into alignment with the opening 4 in the channel, the thumb screw is then projected through the aligned openings, and the swivel cap 9, then attached, as described in the foregoing.

As shown in Figure 4, the nut 6, fits with its parallel sides between the outwardly diverging walls 20 of the channel, whereby 50 it is held against turning.

For the purpose of holding the nut against longitudinal movement in the channel, and maintaining the central opening 19, in vertical alignment with the thumb screw 5, I 55 provide a pair of lugs 21, which may be bent downward along the bending line 22, into contact with the sides of the nut, as shown in Figure 6.

60 By this means, the opening 19, in the top plate *a* is held concentric with the thumb screw. The casing fits sufficiently close around the channel, as to be frictionally held thereon, to prevent longitudinal movement thereof, and it conceals the nut from view, 65 thus rendering the device neat in appear-

ance. The upper wall *a* holds the nut within the channel, and keeps the screw from sliding lengthwise in the member 3.

At opposite ends of the cross member 1, suitable strap hitching means is provided, 70 such as the rings 23, loosely held in the loops 24, which latter are suitably secured, as by rivets, to the cross bar.

As shown in Figure 1, the device is placed on the running board so as to hook over 75 the outer edge thereof, and is then firmly clamped in place. The cross member extends inwardly across the board, and thus supplies (by means of its inner ring 23) 80 a rigid point of attachment for a strap.

Obviously, a number of the carriers may be arranged in a row, whereby long packages may be fastened to the running board.

I claim:

1. A luggage carrier for use in connection with running boards of automobiles, 85 consisting of a channel bar shaped to extend transversely across the top, and around the outer edge of the running board to a point underneath the latter, the channel of the 90 bar facing said running board, means carried by said bar, at a point adjacent the inner and outer edges of the running board, for attaching a tie strap, a clamping screw projected through said channel bar at a 95 point underneath said running board and disposed at right angles to the latter, a nut threaded on said screw positioned within the channel of said bar, and a metallic casing frictionally surrounding said channel bar and loosely surrounding said screw, 100 to keep said nut positioned within the channel.

2. The combination with the clamping means of a luggage carrier for use in connection with the running boards of automobiles, said clamping means including a part having an upwardly opening recess extending underneath the running board, a clamping screw projected, loosely through said 105 part and extending upward toward the underside of the running board, and a nut threaded on said screw and located in said recess, of a metal band having openings 110 loosely receiving said clamping screw and adapted to be bent transversely around said recessed part to cover said recess, and thereby conceal said nut from view.

3. The combination with the clamping means of a luggage carrier for use in connection with the running boards of automobiles, said clamping means including a part having an upwardly opening recess, extending underneath the running board, a clamping screw projected loosely through said part 120 and extending upward toward the underside of the running board, and a nut threaded on said screw and located in said recess; of a long metal band, wrapped transversely around said recessed part and over said nut, 125 130

the band being sufficiently long to overlap at its ends when it is in wrapped position, and having openings to loosely receive said clamping screws, and a pair of lugs one 5 on either side of said band, extending downward at a point immediately adjacent opposite sides of said nut.

4. A luggage carrier for running boards of automobiles, including a part having an upwardly opening recess, extending underneath the running board, a clamping screw projected loosely through said part and extend-

ing upward toward the underside of the running board, a nut threaded on said screw and located in said recess, a long metal band, 15 wrapped transversely around said recessed part and over said nut, and having overlapping ends formed with registering openings through which the clamping screw is passed.

In testimony whereof I affix my signature.

THEODOR R. WILLWERSCHEID.
